UNITED STATES PATENT OFFICE.

ROBERT WILLIAM JONES, OF LONDON, OHIO, ASSIGNOR OF ONE-HALF TO M. F. DUNN, OF LONDON, OHIO.

WRENCH.

No. 908,677.

Specification of Letters Patent.

Patented Jan. 5, 1909.

Application filed June 11, 1908. Serial No. 437,981.

To all whom it may concern:

Be it known that I, ROBERT WILLIAM JONES, a citizen of the United States, residing at London, in the county of Madison and State of Ohio, have invented certain new and useful Improvements in Wrenches; and I do declare the following to be a full, clear, and exact description of the invention, such as will enable others skilled in the art to which it appertains to make and use the same.

My invention relates to improvements in wrenches.

It has for its object to provide a simple, inexpensive and effective contrivance of this character for removing or turning nuts or bolts and for manipulating pipes or other cylindric objects in a ready and expeditious manner.

With the foregoing and other objects in view, the invention consists of certain novel features of construction, combination and arrangement of parts, as will be more fully described and particularly pointed out in the appended claims.

In the drawings illustrating the preferred form of my invention:—Figure 1 is a side elevation thereof; Fig. 2 is a similar view of the same with the handle member removed a short distance from the member equipped with jaws, a portion of the device being removed to disclose more especially the interior of the handle-receiving socket in the member provided with jaws; Fig. 3 is a vertical longitudinal section of the wrench taken on line 3—3 of Fig. 2; Fig. 4 is a modification thereof with the parts adapted more particularly for use as a pipe wrench.

In practicing my invention I provide a member or part 1 equipped with jaws 2 and the handle member 3 adapted for suitable attachment to the first referred to member and its ready removal therefrom as in effecting ready conversion of the device from a nut or bolt wrench into a pipe wrench or for application to other cylindrical objects where its use may be required.

The member 1 which is preferably of general rectangular outline, but slightly tapering in longitudinal direction, has its jaws 2, which are parallel for the greater portion of their lengths upon opposite surfaces, formed with inclined or angular surfaces 5 inwardly from their parallel opposed faces in order to accommodate the different outlines of different shaped nuts or bolt heads. Said mem-

ber 1 is formed with a socket 6 preferably tapering somewhat inwardly with its inner end of more acute meeting inclined walls than are its opposed walls, as at 7, said socket having inwardly extending contracted portions 8, the purpose of which will be apparent later.

The handle member 3 which is preferably of any required length for convenience for grasping, has its inner portion provided with slightly inwardly inclined lateral edges which conform to the corresponding walls of the socket of the member 1 and the intermediate portion of its extreme inner end recessed or cut out as at 9 to conform to and receive the acute tapered portion of said socket, said handle also having extending beyond its tapered recess, terminals 10 to enter the corresponding portions of said socket.

It will be seen that the handle, as it is inserted in place in the member 1, will be wedged in a fixed effective position, thus dispensing with additional means for effecting that purpose and whereby the handle member may be readily removed and inserted without displacing other means of fastening. Also, it will be noted that by means of this arrangement, the handle and member having the jaws for engagement with the object to be manipulated may be readily separated or disassociated as in effecting the conversion of the device according to its intended use as above described.

In the modification as designated by Fig. 4, the member 11 of general outline with the member 1 has its corresponding jaw members 12 adapted for application to a pipe or other cylindrical object, the inner faces of said jaws being straight and somewhat curved respectively in order to obtain the requisite leverage upon the object or pipe manipulated.

The rectilinear or straight surface of one jaw is preferably formed with notches or serrations 13 and which surface may be formed of a piece of steel set into the respective jaw.

It will be understood that the wrench as a whole may be made of malleable metal or steel as desired. Also, it will be noted that a very simple, inexpensive and effective instrument is provided by reason of the foregoing construction and arrangement of parts for its intended purpose.

From the foregoing description taken in connection with the accompanying drawings,

the construction and operation of the invention will be readily understood without requiring a more extended explanation.

Various changes in the form, proportion and the minor details of construction may be resorted to without departing from the principle or sacrificing any of the advantages of the invention, as defined in the appended claims.

10 I claim as my invention:—

15 1. A device of the character described comprising a jaw equipped member having a socket therein with laterally tapering walls, said socket having at its extreme inner end contracted terminals and intermediate said terminals meeting inclined walls, their point of convergence being about central of the socket.

2. A device of the character described embracing a member equipped with jaws and 20 having a socket therein of general inwardly tapering contour with its inner surface formed with meeting inclined surfaces forming an apex central of the bottom of said socket, and a handle member having a corresponding recess at its inner end for engagement with the inner bottom surface of said socket.

25 In testimony whereof I have hereunto set my hand in presence of two subscribing witnesses.

ROBERT WILLIAM JONES.
